UNITED STATES PATENT OFFICE.

ALFRED E. STAFFORD, OF HOPEDALE, MASSACHUSETTS, ASSIGNOR TO DRAPER COMPANY, OF PORTLAND, MAINE, AND HOPEDALE, MASSACHUSETTS.

WARP STOP-MOTION FOR LOOMS.

SPECIFICATION forming part of Letters Patent No. 686,485, dated November 12, 1901.

Application filed July 12, 1901. Serial No. 67,944. (No model.)

To all whom it may concern:

Be it known that I, ALFRED E. STAFFORD, a citizen of the United States, and a resident of Hopedale, county of Worcester, State of 5 Massachusetts, have invented an Improvement in Warp Stop-Motions for Looms, of which the following description, in connection with the accompanying drawings, is a specification, like characters on the drawings 10 representing like parts.

This invention relates to the supporting means for the lease-rods of a loom and the arrangement of the controlling detectors of a warp stop-motion relative to the lease-rods, 15 whereby certain new and useful results are attained, as will more fully appear.

Various other novel features of the invention will be hereinafter described, and particularly pointed out in the following claims.

20 Figure 1 is a cross-section of a portion of a loom with one practical embodiment of the present invention applied thereto. Fig. 2 is an enlarged rear elevation of a portion of the stop-motion apparatus near the left-hand side 25 of the loom, one of the lease-rods being broken off at its end. Fig. 3 is a side elevation of the mechanism shown in Fig. 2 looking toward the left, and Fig. 4 is a perspective detail of one of the supporting connections on 30 heads to which the lease-rods are secured.

Referring to Fig. 1, the loom sides A are each provided with upright stands A^x between the whip-roll W and harnesses H, each stand having bolted to it a depending bracket B, the outwardly-extended ear b^x of the bracket 35 resting on the top of the stand. The ears b^x extend outward slightly beyond the stands (see Fig. 2) and are provided with fulcrum or pivot studs b, which are extended through 40 upright elongated slots c^x in heads C, shown as long round-ended plates (see Figs. 3 and 4) and provided with holes c' near their ends. Suitable pins 2 through the studs b prevent accidental withdrawal of the heads therefrom.

45 The lease-rods L L', which are herein shown as counterparts and substantially elliptical in cross-section, fit snugly into the holes c' in the heads C and are pinned in place by suitable pins 3, so that the heads rigidly connect the lease-rods, rocking movement of the

heads being permitted on the fulera b, and so, too, the lease-rods have a limited rising-and-falling movement by virtue of the slots c^x in the heads. By this structure the lease-rods can readily accommodate themselves to changing 55 conditions in warp tension or movement; but they are held from movement or displacement in the direction of warp travel. A better and more uniform action upon the warps is effected by such construction and arrangement as described.

The inner face of each bracket B is provided with two downwardly-converging shoulders 4, Figs. 1 and 2, and dotted lines, Fig. 3, and a horizontal eye b' extends inward from the 60 top of each bracket between the lease-rods, Fig. 1, and dotted lines, Fig. 2, while a horizontal shelf or rest 5 overhangs on the inner face of the bracket an opening 6 in the lower end of the latter. Flat detector supports or 65 guides d' rest at their lower edges on the shelves 5, said supports extending transversely across the loom from one to the other bracket, with their outer faces resting against the inclined shoulders 4, the supports being 70 tightly held in place at each end by a locking-wedge b², forming the head of an upright sleeve b³, which passes loosely through the eye b', as clearly shown in Fig. 1. A screw-bolt b⁴ is passed down through the sleeve and 75 wedge-like head b² into a threaded hole in the shelf 5, a coiled spring s^x being shown in Fig. 1 between the shelf and the wedge to lift the latter when the screw b⁴ is turned to release or unclamp the detector-supports. The 80 detectors d, shown as thin, flat, and elongated plates longitudinally slotted at 7, are strung upon the supports, upon which they are free to slide up and down, and owing to the inclination and location of the said supports the two 85 series of detectors have their upper ends below the two lease-rods, so that the latter prevent "jumping" of the detectors. Upon one 90 division, as w, of the warp the front series of detectors are hung, and the rear series are 95 hung on the other division w' of the warp adjacent the lease-rods, as clearly shown in Fig. 1, the warps normally maintaining the detectors elevated and in inoperative position. A released detector descends in an inclined 100

path and its lower end is brought into coöperation with the feeling devices, through which the usual stopping means is made operative, the shipper S, Fig. 1, being the only member 5 of such means herein shown. Herein the feeling device is substantially as shown in United States Patent No. 673,826, dated May 7, 1901, and comprises, essentially, a flat plate f, having its edges recessed to present series 10 of square teeth f' and constituting the movable member or feeler proper, it being normally reciprocated in a horizontal plane by suitable means—as, for instance, such as shown in said patent. The fixed member consists 15 of a bar h, its ends entering the openings 6 of the brackets B, the base of the bar on each side being provided with lateral teeth h² triangular in cross-section, Fig. 2, with upwardly-converging faces. Said bar h extends below 20 and between the two banks or series of detectors across the loom, the teeth h² projecting beyond the bar in the path of a released detector, the lower end of the latter being directed by the beveled faces of the teeth h² 25 into the space between the bases of two of such teeth adjacent each other. As in said patent, one stroke of the feeler is positive and the opposite stroke non-positive, and when on its positive stroke the teeth f' register with the teeth h² a released detector will 30 enter the space between two adjacent feeler-teeth and being held from movement by the corresponding stop-teeth h² the non-positive or feeling stroke of the feeler will be arrested, 35 and thereby the operation of the stopping means is effected in a manner well known to those skilled in the art.

Various changes or modifications may be made in the construction and arrangement 40 herein shown and described without departing from the spirit and scope of this invention.

Having described the invention, what I claim, and desire to secure by Letters Patent, 45 is—

1. In a warp stop-motion, two lease-rods capable of limited rising-and-falling movement, two series of controlling-detectors in engagement with the divisions of the warp

and located beneath the lease-rods, guides 50 for the detectors, and a normally reciprocating feeler to coöperate with a released detector of either series.

2. In a warp stop-motion, two series of longitudinally-movable controlling-detectors in 55 engagement with the divisions of the warp, two lease-rods, located respectively above the upper ends of the two series of detectors, whereby jumping of the latter is prevented, guides to direct the movement of the detectors, and a normally reciprocating feeler to co-operate with a detector of either series released by breakage of its warp-thread.

3. In a warp stop-motion, two opposed fixed brackets each having on its inner face downwardly-converging shoulders, a vertically-movable locking-wedge between them, a detector-support inserted between each shoulder and the wedge, means to move the wedge to clamp said supports in position, and a separate device to release the wedge. 65 70

4. In a warp stop-motion, two opposed fixed brackets each having on its inner face downwardly-converging shoulders, two detector-supports, means to detachably lock them 75 against said shoulders, two rigidly-connected lease-rods located above the upper edges of said supports, and means to pivotally support and permit limited rise and fall of the lease-rods. 80

5. In a warp stop-motion, two opposed fixed brackets each having on its inner face downwardly-converging shoulders, a vertically-movable locking-wedge between them, a detector-support inserted between each shoulder and the wedge, a spring to support the wedge, and means to positively depress the latter against the action of the spring, to clamp the detector-supports against the shoulders. 85 90

In testimony whereof I have signed my name to this specification in the presence of two subscribing witnesses.

ALFRED E. STAFFORD.
